UNITED STATES PATENT OFFICE

ROBERT JAMES WALSHE, OF BALTIMORE, MARYLAND, ASSIGNEE TO L. GREIF & BRO.
INC., OF BALTIMORE, MARYLAND

ARMHOLE FOR COATS

Application filed August 30, 1928. Serial No. 303,034.

My invention relates to clothing and particularly to what are known as tropical weight garments, with special reference to tropical weight coats. Such coats are usually made with unlined sleeves, and the armhole seams are piped to give a finish. So far as I know however these piped seams have always been turned in at the shoulder and have not performed any function such as I shall herein-
after describe. The piping of the seams necessitates cording of the armhole, that is, special seaming to hold the piped edges in position so that they will not become displaced and present unsightly ridges on the outside of the garment. This special seaming or cording of the armhole seams has heretofore distinguished a tropical weight coat from the usual tailored garment with lined sleeves.

An object of my invention is to produce a summer coat with unlined sleeves but having a plain front armhole, i. e. having the portion of the armhole seam which is visible when the coat is worn, a plain uncorded seam, the inside of the coat neatly finished without sleeve lining, and each sleeve head supported to avoid the usual unsightly fall of the sleeve from the shoulder seam.

I attain my object by making the usual armhole seam, then pressing this seam open, particularly as to the front and top portion, so that the respective edges are both turned back. The edge of the material forming the sleeve being returned back on itself into the sleeve serves as a support for the sleeve head, and the necessity for cording the top and front of the seam which is the part most conspicuous when the garment is worn, is thus avoided, this method producing a well rounded plain seam shoulder resembling externally the shoulder portion of a garment having a lined sleeve, tailored in the usual manner. For a finish both edges of the fabric forming the shoulder and the sleeve respectively are covered with suitable lining material and in

the preferred form which I shall illustrate and describe this lining material contributes to the support of the sleeve head.

My invention is illustrated in the accompanying drawings, in which

Fig. 1 is a section through the top center of the shoulder in a vertical plane at right angles to the fore and aft plane of the garment.

Fig. 2 is a fragmentary front view of the shoulder, the front of the sleeve being drawn aside to expose a normally hidden portion of the armhole seam.

Fig. 3 is an inside view of the coat showing the armhole and the entire seam connecting the sleeve to the garment.

Fig. 4 is a fragmentary section on the line 4-4 of Fig. 3.

Referring to the drawings, the fabric 1 composing the sleeve, is connected to the fabric 2 composing the shoulder, by means of the seam 3, known as the armhole seam.

As to the portion of the seam at the top and front, the edges 4 of the fabric forming the sleeve and 5 of the fabric forming the armhole are opened, the edge 4 of the sleeve fabric being returned outwardly into the sleeve and the edge 5 of the body fabric being returned inwardly into the body, the two being approximately of the same width. This portion of the seam, i. e. the portion having the edges opened, is then covered with a narrow strip 6 of thin fabric of suitable character. In accordance with the preferred method, one edge 7 of this covering 6 is first laid flat against the top side of the edge portion 4 and sewed to the edge portion 4 of the sleeve fabric 1 by means of a seam 8. The main portion of the strip 6 is then folded over just inside the seam 8 and passed outwardly about the edge portion 4 covering it as to both surfaces. It is then extended inwardly toward the inside of the body of the garment and laid flat against the inside surface 13 of edge 5 of the shoulder cloth form-

ing the seam, after which the inturned edge 14 of the shoulder lining 9, the edge 15 of canvas 16, the edge 5 of the garment fabric, and the edge 17 of the covering strip 6 for the seam are sewed together by means of a seam 10 and the said edges 14, 15, 5 and 17 are then piped or covered by means of piping 11 and the piping is sewed in place, as by means of seam 18.

10 The remainder of the armhole seam of which the shoulder portion thus described, forms a part, is then piped in the usual manner, the edges 4 and 5 of the hidden portion of the seam being brought together and covered by the same piece of piping 11, forming a continuous piped edge which extends around the entire armhole, and the portion of the seam which is closed and piped, i. e. at the lower part of the armhole, is turned inwardly and sewed by means of a special seam 12, (see Fig. 4), which is part of the continuous armhole seam 3. This seam gives a corded effect, as at 19, Figs. 2 and 4.

As a result of following this method, a sleeve having the appearance of the usual tailored and lined sleeve is produced, all exposed portions of the armhole seam being plain and the garment, though unlined, being finished in a pleasing manner as to the armhole and particularly the armhole seam, all the edges of the armhole seam being covered and one of the edges 4 thus covered serving as a suitable support for the sleeve head.

I hereby acknowledge as part of the prior art Letters Patent No. 1,674,572, granted June 19, 1928, to Harry J. Rosche, Jr. and Wm. Schwartz. The support for the head of the sleeve in the Rosche patent is a flange for the edge of the body fabric carried across the seam and extended into the sleeve. My claims are not to be construed as reading on this structure, as my invention consists essentially in turning back the body fabric on the inside of the seam, and turning out the sleeve fabric inside of the head of the sleeve as the sole and sufficient support therefor. The covering material 6 shown in Fig. 1 herewith as already stated is too thin to afford any support, and fulfills the sole function of covering strip or lining.

While I have thus specifically described the embodiment of my invention in the best form known to me at present, nevertheless this specific description is for purposes of definition and not of limitation. I am aware that a number of changes and modifications may be made in matters of detail without departing from the scope and purview of the invention, and it is to be understood that I contemplate all such changes and modifications as fall fairly within the scope of the appended claims.

What I claim is:

1. In a coat, a body, an unlined sleeve, and a continuous armhole seam connecting said

sleeve to said body, the edge of the sleeve fabric being cut with a wide turn over or edge over the top of the armhole, tapering off to a narrow turn over or edge to the butt seam at the lower part of the armhole, said wide edge being covered with a fold of lining material and returned upon itself with said covering on the sleeve side of the seam in contact with the inside of the head of the sleeve so as to support the head of the sleeve, and the edge of the body fabric being turned inwardly from the seam forming a continuous inwardly turned flat flange around the entire armhole.

2. The combination described in claim 1, with the additional element of a cover strip of thin material secured on one side within the armhole and on the other extending over and secured to the returned edge of the sleeve fabric.

3. The combination described in claim 1, with the additional elements of a lining strip of thin material covering the edge and inner face of the returned portion of the sleeve fabric, and secured across the armhole seam to the body fabric of the coat.

4. The combination described in claim 1, having the body fabric of the coat returned back on the body side of the armhole seam, and thin material within the armhole covering the edges of both the sleeve fabric and the body fabric respectively.

5. The combination described in claim 1, having a finished and covered seam extending continuously around the armhole, with the lower edges of the body fabric and the sleeve fabric brought together, and piped or covered in the ordinary manner, but with the upper edges over the top of the shoulder opened out and covered by a separate lining strip of thin material extending around the inside of the head of the sleeve.

6. The combination described in claim 1, with the lower or hidden portion of the continuous armhole seam corded under the armhole, and the upper portion provided with an extension lining strip of thin material covering and secured to the returned edge of the sleeve fabric over the shoulder.

7. The combination described in claim 1, having shoulder fabric, shoulder stiffening and lining turned inwardly from the armhole seam, a lining strip of thin material extending over the shoulder, covering the returned edge of the sleeve fabric, and carried over to the returned edge of the shoulder fabric, and a piping stitched through and forming a cover and finish for the edge of the extension liner, and the edges of the body fabric, stiffener and lining, completely around the armhole.

In testimony whereof I hereunto affix my signature.

ROBERT JAMES WALSHE.
